UNITED STATES PATENT OFFICE.

CHARLES MOUTHUY, OF PITTSBURG, KANSAS.

WOODWORKER'S CLAMP.

No. 891,091.

Specification of Letters Patent.

Patented June 16, 1908.

Application filed January 29, 1908. Serial No. 413,263.

To all whom it may concern:

Be it known that I, CHARLES MOUTHUY, a citizen of the United States, residing at Pittsburg, in the county of Crawford and State of Kansas, have invented new and useful Improvements in Woodworkers' Clamps, of which the following is a specification.

This invention relates to improvements in wood-workers' clamps of the type employed by carpenters, cabinet makers and other woodworkers in the manufacture of panels and other articles formed of parts which are glued together and held in fixed relation until the glue has dried or set and rigidly united the parts together.

It is well known that considerable difficulty is experienced in making panels and parts of this character, owing to the fact that during the process of gluing the panel is liable to become warped or the parts otherwise distorted out of proper relationship, due to climatic conditions, the character of the glue employed and the thickness of the material, the panel clamps of ordinary construction now in common use being incapable of use to overcome these objections and ineffective in requiring the workmen to employ auxiliary means to prevent warping or distortion of the panel during the gluing process.

The object of the present invention is to provide a clamp of simple construction, and capable of being inexpensively manufactured, which will securely clamp the panel in position and at the same time hold the panel so it cannot become warped or distorted and which is also readily and conveniently adjustable for use in gluing different sizes of panels.

With this and other objects in view, the invention consists of the features of construction, combination and arrangement of parts hereinafter fully described and claimed, reference being had to the accompanying drawings, in which:—

Figure 1 is a top plan view of a woodworker's clamp embodying my invention. Fig. 2 is a side elevation thereof. Fig. 3 is a vertical longitudinal section. Fig. 4 is an end elevation. Fig. 5 is a perspective view of one of the adjustable clamping bars.

The clamping device embodying my invention comprises a frame formed of a pair of longitudinal bars 1 and 2, connected at one end by a head or cross-bar 3, rigidly secured thereto in any preferred manner, each of the

bars 1 and 2 being provided with a longitudinal series of vertical holes or perforations 4.

Arranged for sliding adjustment on the bars 1 and 2 are transverse clamping bars or jaws 5 and 6, which are formed with transverse openings 7 for the passage of the bars 1 and 2 by which said clamping bars are rendered slidably adjustable on the latter. The inner clamping bar or jaw 5 is adapted to be adjusted through the medium of a screw 6 shaft 8 revolvably mounted in a threaded bearing sleeve or bushing 9 on the head piece 3 and having a swiveled connection at its inner end, as indicated at 10, with the clamping bar 5, the outer end of said screw 70 shaft being provided with a suitable grip or handle 11. Through the medium of this screw shaft, the bar 5 may be adjusted on the bars 1 and 2 toward and from the head 3. The companion clamping jaw or bar 6 is designed to be slidably adjusted by hand and to be fixed in adjusted position through the medium of the holding pins 12 or the like fitted within certain of the openings 4 in the bars 1 and 2 to bear against the rear edge 80 of said jaw, by which the latter may be held from outward movement on the frame.

In practice, it will be understood that the boards composing the panel rest upon the upper edges of the frame bars 1 and 2 and are held assembled or clamped together between the clamping bars or jaws 5 and 6, the panel being allowed to remain in the clamp until the boards or parts thereof are rigidly united by the drying or setting of the glue.

As hereinbefore stated, the main objection to the use of clamps of ordinary construction is that no means is provided therein to prevent warping or distortion of the panel clamped in the manner described, the workman being required to adopt auxiliary means or different expedients to prevent such warping or distortion. One of the objects of my invention is to overcome this objection and provide means to hold the panel firmly in position, so that the panel as a whole cannot shift vertically or any of its parts become displaced at any time during the period in which they are held in the clamping frame. 100

Arranged to be supported by the clamping bars 5 and 6 is a holding bar 13, which lies above and on a central line between the frame bars 1 and 2. This holding bar 13 is slidably connected with the clamps 5 and 6, preferably 110

- 2
- by providing each of the latter in its upper face with a transverse slot 14 in which the bar 13 fits, the said bar 13 being approximately equal in length to the length of the frame. In order to secure the holding bar in position, one end of said bar is provided with a fixed retaining device 15, comprising a socket member having a lug or finger 16 projecting downward therefrom and adapted 5 to enter a recess 17 in the outer face of the head or fixed cross-bar 3. Slidably mounted on the bar 13 is an adjustable retaining member 18 comprising a socket having a depending retaining lug or finger 19, which is 10 adapted to fit within a receiving recess 20 in the outer face of the clamping jaw 6. The head bar 3 has its upper surface lying in the plane of the clamps 5 and 6 and formed with a transverse recess 21 in its upper edge to 15 receive the adjacent end of the holding bar provided with the retaining member 15, and it will be observed that the inner faces of both retaining lugs or fingers 16 and 19 have a downward and forward inclination, while 20 the inner walls of the recesses 17 and 20 are similarly inclined or under cut, so that when the retaining devices are fitted in the recesses they will be securely held therein against 25 upward movement, thus providing for the firm retention of the bar 13 in applied position against upward vertical strain. The adjustable retaining member 18 carries a set screw 22 to secure it in adjusted position 30 on the bar 13.
- 35 One of the frame bars 1 or 2, or both, if desired, is provided with a scale 24 by which the clamps 5 and 6 may be adjusted relative to each other to clamp a panel of any determined width within the limits of the clamp, 40 which may be made of any desired size to suit the character of the work to be done.
- 45 It will be understood that in the practical use of the device the parts of the panel are laid crosswise on the frame bars 1 and 2 and the clamps 5 and 6 adjusted to engage the opposite side edges thereof to exert a pressure by which the glued joints will be held firmly

in contact. After the panel has been set and clamped in the manner mentioned, the bar 13 is applied by fitting it down into the recesses in the bars 3, 5 and 6, engaging the retaining lug 16 with the recess 17, and finally sliding the retaining member 18 until its lug 19 is engaged with the recess 20 and fixing it in such adjusted position by the set screw 55 22. The bar 13 will thus be secured in position to overlie and bear upon the upper surface of the panel, thus preventing it from lifting or its parts from moving out of proper relative position, whereby warping or distortion will be effectually prevented. 60

Having thus fully described the invention, what is claimed as new is:—

1. A woodworker's clamp comprising a frame, embodying longitudinal bars connected at one end by a cross piece, a pair of clamping bars adjustable on the frame bars, means connected with the cross piece for adjusting one of said clamping bars, the other clamping bar being free for hand adjustment, means for securing the latter named bar in adjusted position, a holding bar, and means for removably securing said holding bar to the cross piece and to the freely adjustable clamping bar. 75

2. A woodworker's clamp comprising a frame embodying longitudinal parallel bars and a cross-bar connecting said bars at one end, sliding clamping bars movable on said longitudinal bars, the said clamping bars and cross piece being provided in their upper surfaces with recesses, means for retaining the clamping bars in adjusted position, a holding bar adapted to be fitted in said recesses, a retaining member on the holding bar to engage the cross piece, and a second retaining member on said bar adjustable thereon and adapted to engage one of the clamping bars. 85

In testimony whereof I affix my signature in presence of two witnesses.

CHARLES MOUTHUY.
